UNITED STATES PATENT OFFICE.

ALBERT SWINDLEHURST, OF MONTREAL, CANADA.

PAPER-GUIDE FOR TYPE-WRITERS.

SPECIFICATION forming part of Letters Patent No. 691,503, dated January 21, 1902.

Application filed April 2, 1901. Serial No. 54,059. (No model.)

To all whom it may concern:

Be it known that I, ALBERT SWINDLEHURST, of the city of Montreal, in the county of Hochelaga, in the Province of Quebec, Canada, have 5 invented certain new and useful Improvements in Paper-Guides for Type-Writers, of which the following is a specification.

My invention relates to improvements in paper-guides for type-writers, and particularly to that class in which two sets of U-shaped bars of graduated heights are supported in two frames above the platen or impression-roller, and each pair of which when operated from the keys is designed to be given 10 a downward swing to a central point between the two sets and directly onto the paper on the platen or roller to give the impression; and the object of the invention is to devise a paper-guide which will not interfere with the 15 free passage of the paper no matter what the width of such may be, which will not be liable to be struck by the type, and thus deleteriously affect such type, and which it will not be necessary to adjust; and it consists, 20 essentially, of the two plates attached to or forming part of the bottom of the type-bar frames and extending laterally inwardly with a curved upwardly-extending lip, such plates extending forwardly under the frame and 25 over the scale-bar, the parts being otherwise constructed and arranged in detail as herein-after more particularly explained.

Figure 1 is a perspective view of portion of a type-writer, showing the parts to which my 30 invention relates. Fig. 2 is a cross-section. Fig. 3 is a detail of one of the plates.

In the drawings like letters of reference indicate corresponding parts in each figure.

A is the platen of the type-writer, which is 40 supported in suitable bearings in the end of the carriage B and is provided with the usual turning-knobs a.

C are the type-bar frames, which are supported on the standards D, forming a portion 45 of the main frame.

c represents the innermost type-bars, the remaining type-bars on the outside increasing in length from inside to outside. The bars are substantially reverse-U-shaped in 50 form, the type being at the top thereof, and their position is shown mainly by dotted lines.

E E are plates, being somewhat in the form of a compound curve in cross-section and formed up with attaching-lugs e e, by which they are fastened to the bottom of the frame 55 C C by the screws e'. The inner ends of each plate E are formed with an upturned curved lip e², preferably straight in cross-section, such lip being on a line with the impression-point on the platen. 60

It is not necessary here to describe the ribbon nor the way it is fed; but it is sufficient to state that the ribbon is brought in between the lips e² at the proper time that the impression is delivered on the paper on the platen 65 from the type on the type-bar midway between the ends of the lip e². The scale-bar F, it will be noticed on reference to Figs. 1 and 2, is supported on suitable arms f, attached to or forming part of the frame. The 70 scale-bar F extends into proximity with the platen, as indicated. The course of the paper is shown by dotted lines in Fig. 2, such paper passing over the platen and the apron A.

Heretofore the fingers that served as a guide 75 for the paper to carry it past the impression-point on the platen were supported on a bar extending from end to end of the carriage above the apron A', the fingers being substantially on a triangular frame, with the 80 points of the fingers extending underneath the type-bar frames onto the scale-bar. Such fingers were longitudinally adjustable on their supporting-bar for different widths of paper, and consequently if the operator of 85 the machine forgot to adjust them properly they might when the carriage was laterally adjusted during the operation come underneath the point where the type strike on the platen, and thereby injuriously affect the type. 90 It was also necessary to adjust them for different widths of paper and for envelops. The laterally-extending portion of the fingers being below the level of the top of the platen also formed an obstruction with which the 95 paper was liable to come in contact, and thereby prevent the paper feeding properly. All these objections are entirely obviated by my construction of plate and lips, which being upturned at the inner ends allow the 100 paper to pass freely underneath in both directions and yet effectually guide the paper

over the platen. The lips being also supported by the type-bar frame will form no obstruction to the impression of the type, as was the case in the old form, where the type 5 might come in contact with the fingers, and thereby prevent any impression being made upon the paper.

What I claim as my invention is—

1. In a paper-guide for type-writers, the 10 combination with the platen and the type-bar frames located above the same separated centrally, of a plate intermediate of the platen and type-bar frames and attached to or forming part of the bottom of each frame and provided with an inwardly-extending lip as and for the purpose specified.
2. In a paper-guide for type-writers, the 15 combination with platen and the type-bar frames separated centrally, of a plate attached to or forming part of the bottom of each frame and provided with an inwardly-extending lip and curved in cross-section, so

as to hold the paper down as and for the purpose specified.

3. In a paper-guide for type-writers, the 20 combination with the platen and the type-bar frames separated centrally, of a plate curved in cross-section and provided with an inwardly-extending upturned lip and having suitable lugs whereby it is fastened to the 25 bottom of each type-bar frame as and for the purpose specified.

4. In a paper-guide for type-writers, the 30 combination with the platen suitably journaled in the carriage, of the type-bar frames 35 above the platen having inwardly-extending portions between the type-bar frames and platen designed to extend over the paper and hold it down as it passes laterally underneath the same as and for the purpose specified. 40

ALBERT SWINDLEHURST.
